UNITED STATES PATENT OFFICE.

JOSEPH L. MODLIN, OF HANDSOM, VIRGINIA.

WATER-HEATER.

1,206,127.

Specification of Letters Patent. Patented Nov. 28, 1916.

Application filed March 28, 1916. Serial No. 87,310.

To all whom it may concern:

Be it known that I, JOSEPH L. MODLIN, a citizen of the United States, residing at Handsom, in the county of Southampton, State of Virginia, have invented certain new and useful Improvements in Water-Heaters; and I do hereby declare the following to be a full, clear, and exact description of the invention, such as will enable others skilled in the art to which it appertains to make and use the same.

The present invention is directed to improvements in water heaters, and has for its object to provide a device of this character which can be conveniently attached to a barrel or tank for heating the water contained therein in a quick manner.

A further object of the invention is to provide a water heater of this nature especially adapted for attachment to a barrel or tank for heating the water therein which being heated serves to scald hogs.

A still further object of the invention is to provide a water heater having associated therewith a shield for preventing the flames from contacting with the barrel or tank and at the same time preventing smoke and sparks from flying upon the attendant.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a side elevation of the device; Fig. 2 is a top plan view; Fig. 3 is a sectional view on line 3—3 of Fig. 1; Fig. 4 is a sectional view on line 4—4 of Fig. 1; Fig. 5 is a sectional view on line 5—5 of Fig. 1; and Fig. 6 is a sectional view on line 6—6 of Fig. 1.

Referring to the drawing 1 indicates a U-shaped pipe which has its ends engaged in one of the ends of the elbows 2, the other ends of said elbows having threaded therein couplings 3, said couplings having heads 4.

In applying the pipe to the barrel or tank

5 the couplings 3 are passed through the openings 6 formed in the barrel or tank and are threaded in the adjacent ends of the 55 elbows 2, and at which time the heads 4 and adjacent ends of the elbows are in clamped engagement with the barrel or tank.

Slidably connected to the sides 7 of the pipe 1 are clamps 8, said clamps having 60 connected thereto plates 9 which carry clamping bolts 10. The clamping bolts 10 are engaged in the slots 11 formed in the shield plate 12, thereby rigidly connecting said plate to the plates 9. It will be noted 65 that the bolts 13 which are carried by the clamps 8 not only serve to pivotally connect the plates 9 to the clamps, but also serve as means for holding the clamps in adjusted positions on the sides of the pipe 1. Thus it 70 will be seen that the shield plate 12 can be adjusted at any angle, or may be folded upon the pipe 1.

The couplings 3 are spaced a short distance above the bottom of the barrel or 75 tank, thus holding the pipe 1 spaced from the ground and in a horizontal position. Water is placed in the barrel or tank to the desired level and a fire started under the bight portion of the pipe 1 so as to heat the 80 water therein, which being heated will circulate thereby thoroughly heating the water in the barrel or tank so that the carcass can be dipped into the water for scalding.

What is claimed is:—
85
In combination with a barrel having openings formed therein adjacent its bottom, a heater comprising a U-shaped pipe, couplings engaged in said opening and engaged with the ends of the pipe for receiving water from the barrel, whereby when a fire is lighted under the bight portion of the pipe the water in said pipe will be heated to create a circulation in the barrel, clamps adjustable longitudinally of the pipe, a shield 90 disposed transversely of the pipe and adjustably connected with the clamps. 95

In testimony whereof, I affix my signature, in the presence of two witnesses.

JOSEPH L. MODLIN.
